UNITED STATES PATENT OFFICE.

JULIAN W. FRETWELL, OF DANVILLE, VIRGINIA.

LOCKED RAZOR.

Application filed April 29, 1922. Serial No. 557,262.

To all whom it may concern:

Be it known that I, JULIAN W. FRETWELL, a citizen of the United States, residing at Danville, in the county of Pittsylvania and State of Virginia, have invented new and useful Improvements in Locked Razors, of which the following is a specification.

One object of my said invention is the provision of a locked razor—i. e., a razor so constructed that its blade is locked against removal and against surreptitious use by servants. Manifestly a razor characterized as indicated may be placed in the hands of an insane man for legitimate use without liability of the patient being able to remove the blade and use the same in a suicidal effort. Also, a razor of the kind stated may be left in his room by the owner without possibility of any person using the razor, the locking means being preferably controlled by a key to be carried by the owner, and manipulation of such key being absolutely necessary in order to dispose the blade for use. After use of the razor the key is introduced and manipulated to put the blade and the razor as a whole out of commission, and the key is then carried away by the owner.

Another object of the invention is the provision in a razor characterized as set forth, of a flexible blade provided with a multiplicity of closely arranged apertures adjacent to each of its edges so that in the event of an insane person seeking to pick at the blade with a view to removing the same, the blade will be broken into fragments and rendered unfit for use.

My improvements are designed more particularly for embodiment in a certain well known type of safety razor, but I desire it distinctly understood that it is within the purview of my invention to embody the improvement in a razor of any type, it being within the purview of my invention to combine any kind of razor blade with means for locking the blade so as to preclude use of the razor by any one except the owner or a person having authority over the razor.

To the attainment of the foregoing, the invention consists in the improvement as hereinafter described and definitely claimed.

In the accompanying drawings, forming part of this specification:—

Figures 1 and 2 are sections at right angles to each other taken longitudinally

through a well known type of safety razor 55 constructed in accordance with my invention.

Figure 3 comprises disassembled elevations of parts embraced in the said razor together with an elevation of the key for controlling the razor.

Figure 4 is a plan view of a blade of flexible character, weakened in accordance with my invention for the purpose indicated.

Similar numerals of reference designate 65 corresponding parts in all of the views of the drawings.

The blade 1 illustrated is of the transversely flexible kind with duplex sharpened edges 2. The blade is also shown as provided with a central aperture 3 and other apertures 4. The multiplicity of minute apertures 5 in the blade 1 as shown in Figure 4 may be employed or may be altogether omitted without affecting the major portion 70 of my invention. I prefer, however, to employ the said minute portions 5 inasmuch as they impart to the blade the capacity of readily breaking into fragments in the event of an insane person working at the edges of 75 the blade in an attempt to remove the same from the remainder of the razor.

In addition to a transversely flexible blade, the razor shown comprises a tubular handle 6, a guard 7 with fingers 8 fixed to one end to the handle 6, a blade clamping cap 8 to which is fixed a shank 9 threaded at 10, and a locking member 11 slidable and rotatable about its axis in the handle 6. Appropriately secured in the heel end of 80 the handle 6 is a member 12, a portion 13 of which extends into the handle so as to limit the outward movement of the locking member 11. Manifestly the member 12 is secured to the handle 6 after the arrangement of the locking member 11 in the said handle.

It will also be noticed that movement of the locking member 11 is limited in one direction by an abutment 14 in the handle, and that the said locking member is provided with a threaded socket 15 and with a key seat 16. The said key seat is for cooperation with the reduced end 17 of the key 18, Figure 3, which key 18 is provided with an appropriate handle 19. The blade clamping cap shown is provided in addition to the stem 9 with studs 20, said studs 100

20 being designed to occupy apertures 21 in

the guard 7 for the ordinary well known purpose.

It will be apparent from the drawings that when the blade 1 is positioned as shown 5 in Figures 1 and 2, the razor cannot be used nor can the blade 1 be removed. To put the razor into condition for use it is necessary to introduce the key 18 through the tubular member 12 and into engagement with the 10 locking member 11 about its axis through the medium of the key until the transversely flexible blade 1 is reduced to a subsequently flat state and so that its edges protrude sufficiently far beyond the longitudinal edges 15 of the clamping cap 8 for shaving purpose. After use of the razor the owner or a keeper having effort over the razor introduces the key 18 and by turning the member 11 returns the parts to the positions shown in 20 Figures 1 and 2, and then takes the key away with him.

When it is desired to clean the razor the member 11 is manipulated through the medium of the key 18 to a sufficient extent to 25 permit of the removal of the cap 8 and the blade 1, and then after the cleaning operation the said blade and cap are replaced, and the member 11 is adjusted through the medium of the key to position the parts as 30 shown in Figures 1 and 2.

Notwithstanding the capacity of function ascribed to my improvement, it will be readily appreciated from the foregoing that a 35 razor of the type indicated embodying the invention is simple and inexpensive in construction and is calculated to last quite as long as an ordinary razor of corresponding type.

I have entered into a detailed description 40 of the construction and relative arrangement of the parts embraced in the present and preferred embodiment of my invention in order to impart a full, clear and exact understanding of the said embodiment. I 45 do not desire, however, to be understood as confining myself to the said specific construction and relative arrangement of parts inasmuch as in the future practice of the invention various changes and modifications 50 may be made such as fall within the scope of my invention as defined in my appended claims.

Having described my invention, what I

claim and desire to secure by Letters-Patent, is:—

55

1. A locked safety razor comprising a hollow handle carrying a guard, a clamping cap having a stem, a transversely flexible blade on the stem and interposed between the guard and cap, and a locking member 60 completely disposed and operable in the hollow handle and engaged with the stem of the clamping cap to secure the blade in an idle position and against removal and provided entirely within the hollow handle with 65 a key portion to be engaged with a key separable from the razor.

2. A locked safety razor comprising a hollow handle carrying a guard, a clamping cap having a stem, a transversely flexible blade 70 on the stem and interposed between the guard and cap, and a locking member disposed and operable in the hollow handle and engaged with the stem of the clamping cap to secure the blade in an idle position 75 and against removal, the said locking member being key controlled, and the key being removable from the hollow handle and separable from the razor.

3. In a razor, the combination of a tubular handle with a guard at one end, said guard having a central aperture and other apertures, a clamping cap opposed to the guard and having a stem extending through the central aperture thereof and into the tubular handle and provided with a threaded portion, a tubular member secured in the heel end of the handle, a locking member movable about its axis in the tubular handle and having a kerf or socket in its heel end and also having a threaded socket receiving a portion of the cap stem, and a transversely flexible blade apertured to receive the stem and studs on the cap and interposed between the said cap and the guard, said locking member being adapted to be operated by a key, and the said key being separable from the razor.

80

85

90

95

4. As a new article of manufacture, a transversely flexible razor blade having a sharpened edge and also having adjacent to said edge a multiplicity of minute, closely arranged apertures.

100

In testimony whereof I affix my signature.

JULIAN W. FRETWELL.
